UNITED STATES PATENT OFFICE

2,470,300

NONREPEAT MEANS FOR CALCULATING MACHINES

Herman Gang, Livingston, N. J., assignor to Monroe Calculating Machine Company, Orange, N. J., a corporation of Delaware

Application March 17, 1948, Serial No. 15,374

5 Claims. (Cl. 235—62)

1

The invention relates to settable means for limiting the registering action of the differential actuators of a multi-cyclic calculating machine to a single cycle, by releasing the set digit entering keys and/or by bringing the actuators to rest.

According to the invention the control of a pre-set non-repeat key is localized to operations initiated by a given key or keys; another operation initiating key effects operation of the non-repeat devices independently of the setting of the non-repeat key, and still other operation initiating keys may be provided in the operation of which no non-repeat action will occur, irrespective of the setting of the non-repeat key.

The invention consists in the novel construction and combination of parts, as set forth in the appended claims.

In the accompanying drawings, illustrating the invention:

Figure 1 is a longitudinal vertical section of a calculating machine to which the invention is shown as applied.

Figure 2 is a left side elevation of the machine, with casing removed.

Figure 3 is a horizontal section of the machine.

Figure 4 is a right side elevation of the machine, with casing removed.

Figure 5 is a detail elevation of the non-repeat key and plus-minus bar mechanism.

Figure 6 is a detail elevation of the non-repeat key and a setup key mechanism.

Figure 7 is a detail elevation of the non-repeat key and a modified form of setup key mechanism.

Registration

The invention is shown as applied to a calculating machine disclosed in the co-pending application of Herman Gang, Serial No. 8,547, filed February 16, 1948, and entitled Multiplier entering means for calculating machines.

According to said disclosure, amounts set up on the keyboard by the depression of selected digit entering keys 18 (Fig. 1) are set in the differential actuators 5 through the medium of selector bails 19. Upon rotation of actuator shaft 4, forwardly or reversely, such amounts are transmitted, additively or subtractively, through intermediate gearing 545 to the numeral wheels of a register 13.

Actuator shaft 4 is driven by power from an electric motor 1, through a differential gear clutch and reversing unit 105, 110 (Fig. 2), gears 408 and 355, shaft 350 and gearing 405 (Fig. 4). The elements 105 and 110 of the differential gear unit

2

are driven oppositely, and are engageable respectively by arms 114, 113 of a clutch yoke 111 (Fig. 2), engagement of arm 114 with element 105 effecting additive rotation of the actuators, and engagement of element 113 with element 110 effecting drive of the output gear 408 of the differential unit in the opposite direction, and subtractive rotation of the actuators 5.

Calculation in any of the four rules of arithmetic may be controlled by the manipulation of plus and minus bars 120, 121 (Figs. 4 and 5), having link connection 123 with a rock shaft 125. A setting plate 128, mounted upon shaft 125, is provided with lugs 128', engaging an extension 130 of clutch yoke 111. Depression of plus bar 120 will rock shaft 125 in a clockwise direction as viewed in Figure 5, rocking clutch yoke 111 clockwise as viewed in Figure 2 and engaging arm 114 with clutch element 105. Depression of minus bar 121 will lock shaft 125 and clutch yoke 111 in the opposite direction, engaging arm 113 with clutch element 110.

Normally the clutch yoke is disengaged and the differential actuators 5 are brought to rest as they next come into their full cycle position following manual release of key 120 or 121. This is effected as follows: When shaft 125 is rocked, the rear end of a spring biased lever 134 (Fig. 2) is depressed by contact with a roller 133 mounted on said lever, of one or the other of two opposed cam faces formed on setting plate 128. A pawl 136 is mounted on the rearward arm of lever 134, said pawl having a lug normally lying in front of a lug formed on a trigger 31. Rocking of lever 134 will depress pawl 136, allowing the lug thereof to fall beneath the lug of trigger 31, so that upon release of the operating key and return of lever 134 to normal position, trigger 31 will be lifted. In the normal position of the parts trigger 31 is in restraining engagement with a spring biased pawl 25 mounted upon a stop arm 24. Lifting of trigger 31 will release pawl 25, allowing said pawl to be moved counterclockwise by its spring. A rock arm 22 is connected by link 21 and crank arm 20 with the shaft 350, said arm oscillating during the cycling of the differential actuators. Pawl 25, having been released, will fall behind a shoulder 27 of arm 22, as said arm moves through its rearward dead center position, corresponding to the full cycle position of actuators 5. Continued movement of shaft 350 will now drive arms 22 and 24 as a unit in clockwise direction, and one of two opposed cam faces formed in a rearward extension 144 of arm 24 will, through pin 145, centralize the clutch yoke 111 and break

the drive. Spring 29 acting upon the arm 24 will now restore the actuators 5 to full cycle position, and pawl 25, contacting the end of trigger 31 will be lifted out of engagement with the lug 27 of arm 22.

The digit entering keys 18 are spring biased in raised position, and upon manual depression are held in operated position by locking bails 432 (Fig. 3), engaging suitable notches in the key stems. A key releasing bar 431 extends laterally across the keyboard and is provided with lugs engaging the locking bails 432. Endwise movement of the bar 431 will therefore rock bails 432, against the tension of their springs, thereby releasing any keys 18 which have been set into operative position.

Non-repeat

Registrations initiated by the plus and minus bars 120, 121 may be limited to a single cycle by settable non-repeat means.

This means is operated by a cam 419 (Fig. 4) mounted concentrically and having lost motion connection with a gear 420, driven from the differential actuator drive train by gearing 570. Due to the lost motion connection, cam 419 will engage a pendant 418, mounted upon a lever 421, during the last portion of an actuator cycle in either direction of rotation. Pendant 418 is connected with lever 421 by a stud 744, and at its lower end has slotted engagement with the fulcrum 745 of said lever. This slotted engagement permits independent movement of the pendant, which forms a normally ineffective element of the non-repeat train. When however pendant 418 is held as a rigid extension of lever 421, cam 419 will operate said lever, and the upper end thereof will contact one arm of a bell crank 430, the other arm of which engages the key releasing bar 431 (Figs. 3 and 4), so that operation of lever 421 will clear the keyboard.

Bell crank lever 430 has engagement with a second bell crank lever 433, having an arm engaging a bar 434, extending transversely across the machine, said bar at its other end engaging one arm of a bell crank lever 435. The other arm of bell crank lever 435, is designed to contact with a cam extension 436 (Fig. 2) of an intermediately fulcrumed lever 437 having at its rear end pin and slot engagement with the trigger 31 of the stopping means. Operation of lever 421 will therefore act to trip trigger 31, so that the clutch yoke 111 will be neutralized and the actuators brought to rest in full cycle position at the end of their first cycle of operation.

Pendant 418 may be held rigid with lever 421, under the joint control of the depressed plus and minus bar and of a preset non-repeat key 410 (Figs. 4, 5 and 6). This joint control is effected through a guide abutment 746 pivotally mounted upon a slide plate 747 having cam surfaces engaged by pins 748, 749 mounted in the stems of the plus bar 120 and minus bar 121 respectively. The pivot point of guide abutment 746 is intermediate its length, the lower arm of the member being designed to contact with the lower end of the pendant 418, while the upper arm of the abutment member is freely movable, so long as the non-repeat key 410 remains undepressed. Under these conditions, depression of the plus or minus bar will effect an idle rocking of the abutment member 746 and pendant 418 will be allowed to pivot idly around point 744, and lever 421 will not be operated. When, however, non-repeat key 410 lies in depressed position, a lug 750

of said key will lie in the path of movement of the upper arm of abutment member 746, and upon operation of the plus or minus bar, clockwise rocking of the abutment member being prevented, the lower arm of this member will hold the lower end of pendant 418 in its rearward position, holding the contact portion of said pendant in the path of movement of the cam 419, so that pendant 418 and lever 421 will act as a unit to effect the non-repeat adjustments. The abutment member will be locked in this position during the non-repeat operation by means of a spring biased latch 751 engageable with slide plate 747 as said plate is moved into operative position. During the action of the stopping means, latch 751 is released by engagement thereof by rocker 752 (Fig. 4) having operating connection (not shown) with stop arm 24. In order that latch 751 may not reengage slide plate 747 after the machine is stopped, in case the operation key is held depressed, a spring biased blocking slide 753 (Fig. 5) is mounted on latch 751 and is displaced by slide plate 747 when said plate is moved to operative position, to allow the engaging lug of the latch 751 to drop back of the corresponding lug of the slide plate. Upon release of latch 751, however, blocking slide 753 will snap over the lug of the slide plate and prevent reengagement by pivotal movement of the latch.

For convenience of retraction, non-repeat key 410 has connection through a yoke 411 (Fig. 6) with a repeat key 409, so that depression of either key will act to lift the other key. A toggle spring serves to hold yoke 411 in either adjusted position.

The control of the non-repeat key being localized to operations effected by the plus and minus bars, it will be obvious that other keys may be provided whereby a number of consecutive cycles of operation may be effected without regard to the setting of the repeat and non-repeat keys. It may also be desirable to provide an operation key manipulation of which will always result in a single cycle registration, irrespective of the setting of the repeat and non-repeat keys. Such a key is disclosed in co-pending application Serial No. 8,547, above referred to, as a means for entering multiplier or dividend values into a set of multiplier storage wheels 524 (Fig. 3) or into the register wheels 13, respectively. Further, this co-pending application discloses a modified form of this value entering mechanism in which a cycle of additive registration is followed by a cycle of subtractive registration, the non-repeat means operating at the end of each cycle, first to stop further additive rotation of the actuators and thereafter to stop the machine and clear the keyboard. The present invention is usable also in connection with this two cycle entering or setup mechanism, as indicated in Figures 4-6, but reference is made to application Serial No. 8,547 for the details thereof, since they are not directly pertinent to the present invention. The two cycle setup key 526 (Fig. 6) will set the non-repeat mechanism to active position as follows:

A pawl 754 is mounted on the stem of the setup key 526 and, during depression of the key will engage one member of a toggle linkage 755, normally holding lever 756 in raised position. Toggle 755 being broken by the action of pawl 754, lever 756 will be moved downwardly by its spring (not shown), bringing a pin 757 of said lever into contact with a cam face formed in a

slide 758, the forward end of said slide having a shoulder engaging a pin in the lower arm of abutment member 746. Depression of key 526 and breaking of toggle 755 will move slide 758 rearwardly, moving abutment member 746 against the lower end of pendant 418 to render the non-repeat devices operative. The lower end of the abutment member 746 may be moved into this position irrespective of the setting of the repeat and non-repeat keys, the adjustment being held by engagement of a spring biased latch 759 with slide 758. At the end of the operation toggle 755 will be restored to normal condition and rocker 752 will operate to release latch 759.

Control of the non-repeat devices by a one-cycle setup means is illustrated in Figure 7, wherein parts similar to those shown in Figures 4-6 are given corresponding reference numbers, distinguished by the exponent'.

According to this modified form the setup key 526' is provided with an extension overlying the pin 748' in the stem of plus bar 120', so that depression of the setup key will initiate operation of the differential actuators. Key 526' is also provided with a pin 760 overlying a cam portion of slide 758' and acting to move said slide rearward upon depression of the key, thus rocking guide abutment 746' into its non-repeat position. The parts will be held in this position by latch 759', and released by rocker 752', re-latching of plate 758' before the restoration of the parts being prevented by a blocking slide 761, similar to the blocking slide previously described in relation to the plus-minus bar slide plate 747.

I claim:

1. In a calculating machine having a register, cyclically operable differential actuators therefor, cycling means for said actuators, devices adjustable to enter values in said actuators, and an operation key manipulable to control registering movement of the actuators by said cycling means; normally inactive non-repeat means operable by said cycling means to limit the registering action of said actuators to a single cycle, including a settable non-repeat key, a member movable in time with the actuators, a transmission train driven by said member and including a normally ineffective element, a guide abutment settable

conjointly by said non-repeat and operation keys to hold said transmission element in effective condition, a second operation key, and a slide operable under control of said second key to set the abutment into holding position independently of the non-repeat key.

2. A calculating machine according to claim 1, wherein the first-named operation key is freely retractable upon manual release, and in which is provided a slide plate operable by said first-named key and having operating connection with the guide abutment, a latch acting to hold said slide plate in operated position, and a member driven in timed relation with the movement of the differential actuators and contacting with and releasing the latch.

3. A calculating machine according to claim 2, wherein is provided a spring biased blocking slide mounted on the latch, said blocking slide being displaceable by the slide plate in the movement thereof to operated position and acting upon release of the latch to prevent re-latching of the operated slide plate.

4. A calculating machine according to claim 3, wherein is provided a second latch, releasable by the timed latch releasing member and acting to hold the slide related to the second operation key in operated position.

5. A calculating machine according to claim 4, wherein the guide abutment consists of a member intermediately pivoted upon the slide plate, and in which a lug is provided on the non-repeat key, settable with said key into the path of movement of the free arm of said member.
